CLAIM

The ornamental design for a dicing machine, as shown and described.

DESCRIPTION

FIG. 1 is a front elevation view of a dicing machine showing my new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and,

FIG. 8 is a perspective view of the dicing machine shown in a closed configuration.

The broken lines depict portions of the article that form no part of the claimed design.

1 Claim, 8 Drawing Sheets
